WILLIAM HARPER, JR., OF NEW BLOOMFIELD, PENNSYLVANIA, ASSIGNOR TO AMERICAN GAS TURBINE CORPORATION, OF NEW YORK, N. Y., A CORPORATION OF DELAWARE.

INTERNAL-COMBUSTION ENGINE.

Application filed August 18, 1923. Serial No. 658,035.

This invention relates to internal combustion engines, and has particular reference to means for increasing the efficiency of compression type reciprocating piston engines as now commonly constructed.

5 In the common type of engine compression is obtained by proportioning the piston displacement to the free space in the cylinder head, while the heat of combustion is utilized by the working piston or is lost in the cylinder walls and exhaust. During compression, the combustible mixture may absorb some heat from the cylinder walls, and of course is somewhat raised in temperature 10 by the compression. It is also common to apply a small amount of heat to the combustible mixture before compression for better vaporization of liquid fuel. A substantial amount of heat cannot therefore be added 15 to the mixture before or during compression, or the compression raised to increase efficiency in present types of engines because of preignition with consequent hammering and loss of power due to an explosion or 20 detonation before the compression stroke is completed.

If the temperature and compression of the charge be materially raised during the compression stroke and any detonation or advanced ignition resulting therefrom be utilized 25 in producing a forward rather than a backward torque on the rotary element, an increased overall efficiency of the engine is produced.

30 According to this invention, such result is obtained without preignition in a multi-cylinder engine by connecting through the shortest straight passage, a working cylinder when under high pressure of burning 35 or incandescent gas, to a compressing cylinder or at lower pressure so as to effect a transfer of heat and pressure to the compressing cylinder substantially before the limit of movement of the compression stroke of the 40 piston. I am aware that it has heretofore been proposed to supercharge a compressing cylinder from a working cylinder either indirectly with inert cooled gas from an intermediate chamber, or to transfer flame for 45 ignition of the compressed charge. This invention differs from such proposals in not being subject to the limitation inherent there-

in as to the time or position in the compressing stroke at which the supercharge is to be admitted to avoid preignition, and also by 55 providing a straight passage of minimum length for direct flame transmission without quenching.

This application contains features common to my previous application S. N. 427,475, filed December 1, 1920, and S. N. 485,499, filed July 18, 1921. In the former the cylinders carried by the rotor are radial and the differentially driven valve carried inlet ports, cross firing ports and exhaust ports for the 60 entire charge, the pistons being actuated by yokes travelling with the rotor on stationary eccentrics, with hand controlled mechanism for varying the timing of the valve. In the later application, the valve and piston drive are the same, but the valve is tapered and provided with means for automatically unseating it to prevent sticking when expanded by heat. Instead of being radial, the cylinders are tangentially disposed to an inner circle 65 at such angle that a direct forward torque is produced by the explosion even before the piston reaches dead center during the compression stroke. In the engine of this application the above features of piston and 70 valve drive and tangential cylinders are employed, together with a main exhaust system controlled by the piston and leading the bulk of the exhaust heat away from the valve. The final or scavenging exhaust is through 75 the valve, but this exhaust is at such low temperature as not to cause trouble in valve lubrication or sticking due to uneven expansion. In connection with this main exhaust system a further valve mechanism is 80 provided for the purpose of preventing back fire into the cylinder at the beginning of the compression stroke before the main exhaust port is closed by the piston to the exhaust from another cylinder. The engine of this 85 application also comprises various improvements in details of construction including water circulation, accessibility, etc. In combination with the conical valve is also provided a balancing device to oppose the unseating moment due to cylinder pressure, 90 whereby a light seating spring can be used, instead of one resisting the longitudinal thrust of the maximum cylinder pressure.

In the accompanying drawings,

Fig. 1 is a longitudinal vertical cross section of the engine,

Fig. 2 is a transverse vertical cross section.

5 Fig. 3 is a detail section on an enlarged scale through the valve, showing a position at the commencement of supercharging and cross ignition,

Fig. 18 shows a development of the ports in a stationary sleeve preventing preignition,

45 Fig. 19 shows a section of the valve and shaft through which supercharging and cross ignition occur, and

Figs. 20, 21, 22 are views showing the mechanism for manually controlling the rotary valve timing for supercharging and cross ignition.

The invention comprises a base casing 1 with a removable top 2 and a removable end casing 3 having mounted therein in bearings 4, 5, a rotatable tubular shaft 6 having fixed thereto a rotor casting 7 carrying five tangentially set cylinders 8, the cylinders and shaft rotating as a unit in the casing 1, 3.

50 Mounted on a fixed portion of the casing as the ring 9 is an eccentric ring 10, having a T-shaped track 11 in which run the yokes 12 carrying wrist pins 13 connected to the pistons 14, the wrist pins 13 being in tubes 15 which slide in slots 16 in the cylinders 8.

55 17 are water jacket spaces cored in the rotor casting surrounding the cylinder as shown in Figs. 1, 2, 4 and 8, and providing for centrifugal water circulation as shown in Fig. 8, the water coming in through pipe 20 passing by passage 21 within the shaft extension

22 to passage 23 in detachable end plate 24, thence by key tubes 25, which key the rotor casting to the shaft 6, thence by passage 26 in flange 27 of shaft section 28 to passage 29 in the cylinder jacket, thence around the cylinder in space 30, thence return to the exhaust side of the cooling system through alternate key tubes 31, passage 32, pump 33 and exhaust 34 to a radiator or other cooler and thence to the intake 20, providing a combined centrifugal and forced cooling circulation. As shown herein, three of the key tubes 31 are exhaust tubes and the remaining two 25 are inlet tubes, the volume of exhaust water being slightly greater than intake water owing to the expansion.

75 The charge inlet is by pipe 35 through charge mixing device 36 rotating with the rotor, see Figs. 9, 10 to interior 40 of valve body 41. The valve body 41 is cylindrical to bear within shaft 6 and carries a driving gear 42 and at the other end is attached conical valve section 43 with valve inlet ports 44. Intermediate shaft section carries five ports 45 registered with cylinder ports 46, three valve ports 44 serving the five cylinders owing to the differential rotation of the valve within the shaft. The valve also carries three auxiliary exhaust ports 48, 48, 48, and intervening cross firing and supercharging ports 49, 49, 49, showing in section in Fig. 19 arranged so as to provide a straight passage between the working cylinder and the second succeeding cylinder under compression to be supercharged and fired through the straight cross passage in the valve. I have found that the quenching effect of bent or angular passages and the gas flow retardation thereof prevent cross firing and supercharging, necessitating straight passages of minimum distance between cylinders as shown herein:

85 The cross firing chamber 53 thereby formed between the ports 49 also enables a hot wire 54 to be provided for starting ignition, this hot wire being connected on one side by electrode 55 which in turn is carried by a block 56 in electrical contact with a plug 57 and plunger 58 controlled by spring 59 connected to terminals 60 for a battery or other source of heating current, the other side of hot wire 54 being grounded on the shell 61 and thence through the center of charge distributing vane 36 to the end frame 65, or ground, so that no short circuit is made around the hot wire 54.

90 It is important to provide proper firing port design in order to avoid quenching effect, and such a design is shown in Fig. 9 wherein the nipples 66 carrying the narrowed ports 49 are screwed into the valve body 43 and into the firing chamber body 67, see Figs. 9, 19 and providing charge inlet passages 68 around the cross fire chamber so as to furnish free and ample charge inlet passage area to the valve inlet ports 44, and thence through 100

shaft port 45 and cylinder head port 46 to the cylinder during the suction or outward stroke of the piston.

The exhaust of the engine of this invention 5 occurs practically in three stages:

(1) The initial exhaust is the supercharging and ignition exhaust from the working cylinder through ports 49 and chamber 53 to the second succeeding or compressing 10 cylinder.

(2) The main exhaust which is through cylinder ports 70, see Figs. 4 and 17, and

(3) The residual exhaust through cylinder head port 46, shaft port 45, and valve exhaust port 77 and tubular valve 72 carried by valve body 43 to the main exhaust passage 73.

The initial or supercharge and cross firing exhaust has already been sufficiently described, and the timing is effected by manual 20 means to be hereafter described. The point at which this may occur will vary according to the compression, since the firing cylinder pressure must exceed the compressing cylinder pressure in order to effect the transfer. I 25 have obtained satisfactory results at all points between 80° in advance of innermost piston position. Preferably the axes of the cylinder are tangent to a circle whose radius is equal to one-half the piston stroke, resulting in a 30 five cylinder engine whose dead center is practically about $82\frac{1}{2}^\circ$ in advance of inner piston position. Ignition at any point inside of $82\frac{1}{2}^\circ$ therefore occurs during a period of increasing compression but owing to the tangential cylinder arrangement, together with the yoke, eccentric ring, and eccentric construction and arrangement, all knocking on bearings, connecting rods, etc. is obviated. This construction is best understood from a 40 study of Fig. 2, which shows the tangential cylinders and power transmission elements with their large sliding surfaces and precise fitting, yet elastic, makeup, with no substantial leverage to cause any appreciable knock.

45 Of the two substantially horizontal pair of cylinders in Fig. 2, that at the left is working and the other compressing. Cross firing is just taking place between them, but of course by changing the valve timing, cross fire may be made to occur later or at the end of the compression stroke.

The main exhaust will be understood from Figs. 1, 4, 5, and 17. The cylinder ports 70 open into a passage 71 cast in the side of the 55 rotor casting (Fig. 4) and are closed by plate 24, but run in a curved direction as shown so as to permit of water jacketing between, to exhaust passage 74 which is controlled by ports 75 in the cylindrical portion of tubular 60 valve 72 mounted on valve body 43, and thence leading to main exhaust passage 73. This additional control of exhaust port 74 by an auxiliary valve is desirable in a four cycle engine because ports 70 are opened at 65 the end of the suction stroke and without be-

ing closed by the space between ports 75 would possibly permit hot exhaust gas to be drawn into exhaust ports 70 into a cylinder just completing the suction stroke, or the exhaust from other cylinders might back fire. 70

Back firing is prevented by the arrangement shown or an equivalent. It is further to be observed that valve 72 being carried by the differentially rotatable inlet valve body requires three ports 75 to serve five cylinders. 75

The main advantage of this arrangement is that the temperature of the valve body 43 is kept very low, owing to the main heat from the main exhaust being diverted past the conical portion of valve body 43, thus enabling the latter to be easily lubricated and fitted without excessive and unequal expansion due to the transfer of so much heat in such a small space.

It still remains to scavenge the cylinder 85 by the inward stroke of the piston, which is accomplished through the cylinder ports 46 co-operating with exhaust ports 48 in valve body 43, these ports leading through one of three ports 77 in conical valve 72, see Fig. 90 18. This portion of the exhaust is satisfactorily accomplished without overheating of the valve body both because of the circulation of inlet gas within the valve body and also because the temperature of the exhaust 95 during the scavenging stroke is very low due to the expansion through main exhaust ports 70. The exhaust tube 73 exhausts through ports 79 into exhaust pipe 80, and is surrounded on one side by water inlet passage 21 100 and on the other by water exhaust passage 32 as before described.

The conical valve body 43 is held seated by spring 59, and the tension of spring 59 is adjusted by thumb screw 83, see Figs. 1, 9. 105 The driving gear 42 of the valve meshes with gear 85 on stud shaft 86 mounted in adjustable arm 87. Gear 85 is connected to larger gear 88 which in turn meshes with gear 89 carried by the rotor, thus producing the 110 differential drive between the rotor and the valve. In a five cylinder engine the valve is driven one-sixth slower than the speed of the rotor and the ratio varies with the number of cylinders being one-eighth slower for 115 a seven cylinder engine and can be figured out for other number of cylinders. This enables a differential valve having three inlet, three exhaust, and three cross firing and three main exhaust controlling ports to function for a five cylinder engine, and also provides for the necessary lap of valves.

To shift the timing, arm 87 is provided with a curved rack 92 which meshes with a pinion 93 on a hand shaft 94, so that by turning the hand shaft 94 the differential valve is shifted relatively to the rotor. Set nut 95 holds the adjustment. This mechanism permits variation of timing of the engine during operation which is a very important 130

feature. 96 is a rim or guide plate fitting in a slot in the end of arm 87 to hold it in line.

A geared drive, as to pulley 100, can be taken off from gear 89 through gear 101 on shaft 102.

The skew gear 42 fixed on valve body 41 meshes with a similar internal gear or cam 91 fastened to gear 90, and set to have a normal tendency to move the valve longitudinally to the left in Figs. 1, 9, 11 against spring 59, the tension of the spring being adjusted to resist this back thrust of the skew gears, except when upon tendency of the valve to stick on the conical seat in the shaft, as by expansion or lack of lubrication, the thrust of the gears overcomes the spring and allows the valve to unseat itself automatically. The gears 85, 88, etc. are also skew gears for quietness in running.

Although there is not much longitudinal thrust in a conical valve from cylinder pressure, it is found that a relatively heavy spring 59 is required in a high pressure engine to hold the valve down. By balancing out this thrust, a lighter spring can be used, the valve stays down instead of vibrating into and out of the seat, and less driving power is used.

The tube 55 has a slot 110 through the insulation 111 to admit cylinder pressure to annular space 112 thence by port 113 to balancing cylinder space 114. The fixed head 115 is directly on the valve body 61 and transmits the thrust to the forward (right) end of the valve through nipples 66. The movable head 116 slides on tube 117 but thrusts against shoulder 118 on body 119 which slides through vane ring 26 and thence through thrust bearing 120 to engine frame 65. The tube 119 slides over the cylinder body, and sliding head 116 has a packed fit as shown in the cylinder body. The sliding movement of head 116 relatively to shoulder 118 provides for expansion, and wear of the valve in the seat. The cylinder pressure thrust on the valve is thus balanced out, leaving the seating pressure practically determined by the tension of spring 59. The balancing pressure is determined by the area of cylinder head 115, to be more or less than the cylinder pressure tending to unseat the valve by overcoming spring 59. The present construction is of especial advantage in an elongated conical valve of relatively slight taper, but is applicable to all types of rotary conical valves wherein unseating from cylinder pressure may occur. By tapering block 57 to enlarged ends as shown, the oil tends to centrifugally travel towards the ends and lubricate the block ends in blocks 56, 58. The round ended block 57 also permits slight disalignment due to bearing or valve wear, etc., without getting out of order.

Starting ignition is effected by a compressed charge in a compressing cylinder flowing backward through ignition port 49 into

chamber 53 under sufficient compression to ignite and then flash back through port 49 into the compressing cylinder, with slight loss into the second succeeding cylinder during its working stroke, which may, if there be sufficient charge present, fire this cylinder also shortly after the compressing cylinder fired. Starting ignition is easily obtained in this manner.

The engine is mostly oiled by centrifugal force as described in the aforesaid earlier applications, the spiral oil grooves in the valve and other parts not being shown herein because disclosed in the aforesaid applications.

Centrifugal force in this engine may cause cylinder oil from the piston and differential valve lubrication to collect on the piston head, to discharge which an oil slot 103 with passage 104 leading out through the casting is provided just above ports 70 on the leading or highest part of the cylinder which is just cleared by the piston, see Figs. 2 and 4, and the piston heads are slightly dished outwardly as shown in Fig. 1 so that any oil or oil spray collected by the piston head is centrifugally discharged through this port and passage into the casing, and thence used again.

The engine of this invention embodies a number of outstanding inventions, among which are that it is balanced during operation, only requires starting electrical ignition but can be run on electrical ignition if desired, is very flexible in control owing to ability to shift the valve while running to vary the timing, is highly efficient because of the supercharging and cross ignition, the valve is maintained cool and hence without objectionable tendency to stick, score or wear and with ample lubrication, and the engine as a whole is adequately cooled and lubricated. Various modifications and changes may be made in the details disclosed without departing from the broad scope of the appended claims.

I claim:

1. A combustion engine comprising a cylinder, a piston therein, driving connections for the piston, a rotatable tapered valve controlling the passage of hot gas from the cylinder through its tapered portion, and means controlling the passage of another portion of hot gas from the cylinder around said valve.

2. A combustion engine comprising a cylinder, a piston therein, driving connections for the piston, a valve controlling the passage of a portion of the hot gases from the cylinder, means controlling the passage of another portion of the hot gases from the cylinder around said valve, means for rotating the valve, and means for adjusting the valve timing during rotation.

3. In a combustion engine, a rotor including diverging cylinders each having a gas port and combustion space at the inner end, a piston in each cylinder, means for recip-

- roating the pistons during cylinder rotation, a rotary valve concentric with the cylinder movement having inlet and exhaust passages cooperating with said port, means for driving the valve, and means controlled by the piston for discharging the main exhaust independently of said valve.
4. In a combustion engine, a rotor including diverging cylinders each having a gas port and combustion space at the inner end, a piston in each cylinder, means for reciprocating the pistons during cylinder rotation, a tapered rotary valve concentric with the cylinder movement having inlet and exhaust passages cooperating with said port, means for differentially driving the valve, and means controlled by the piston for discharging the main exhaust independently of said valve.
5. In a combustion engine, a rotor including diverging cylinders each having a gas port and combustion space at the inner end, a piston in each cylinder, means for reciprocating the pistons during cylinder rotation, a tapered rotary valve concentric with the cylinder movement having inlet and exhaust passages cooperating with said port, means for differentially driving the valve, means for balancing the valve against cylinder pressure, and means controlled by the piston for discharging the main exhaust independently of said valve.
6. In a combustion engine, a rotor including diverging cylinders each having a gas port and combustion space at the inner end, a piston in each cylinder, means for reciprocating the pistons during cylinder rotation, a valve concentric with the cylinder movement for controlling a portion of the exhaust from said cylinders, means for passing the main portion of the exhaust around said valve, and means to prevent back fire from said last mentioned exhaust means.
7. A combustion engine comprising a cylinder, a piston therein, driving connections for the piston, a rotatable tapered valve for controlling the passage of hot gas from the cylinder, a tapered valve seat, means for holding the valve on its seat, means for controlling the unseating effect of cylinder pressure, and means for driving the valve in timed relation to the piston.
8. The combination with a tubular ported shaft carrying cylinders having registering head ports, of pistons in the cylinders, means for reciprocating the pistons as the cylinders rotate, a tubular driven valve within the shaft having a charge inlet passage and ports co-operating with said cylinder ports to admit charge, means for cross firing and supercharging a compressing cylinder from a working cylinder, and means for exhausting the working cylinder.
9. The combination with a tubular ported shaft carrying cylinders having registering head ports, of pistons in the cylinders, means for reciprocating the pistons as the cylinders rotate, a tubular driven valve within the shaft having a charge inlet passage and ports co-operating with said cylinder ports to admit charge, means for cross firing and supercharging a compressing cylinder from a working cylinder, and means for exhausting the working cylinder partly through said valve and partly around said valve.
10. The combination with a tubular ported shaft carrying cylinders having registering head ports, of pistons in the cylinders, means for reciprocating the pistons as the cylinders rotate, a tubular driven valve within the shaft having a charge inlet passage and ports co-operating with said cylinder ports to admit charge, means for cross firing and supercharging a compressing cylinder from a working cylinder, and means for exhausting the working cylinder partly through said valve and partly around said valve through a piston controlled cylinder port.
11. The combination with a tubular ported shaft carrying rotatable cylinders tangent to a circle concentric with their movement having registering head ports, of pistons in the cylinders, means for reciprocating the pistons as the cylinders rotate, a tubular differentially driven valve within the shaft having a charge inlet passage and ports co-operating with said cylinder ports to admit charge, means including transverse passages through the valve between said inlet passages for cross firing and supercharging a compressing cylinder from a working cylinder, said transverse passages having constricted ends adjacent the valve periphery, and means for exhausting the working cylinder.
12. A combustion engine of the tangentially arranged rotating cylinder type with a driven tubular valve within the shaft, having a transverse cross firing and supercharging passage with constricted ends adjacent the valve periphery for connecting a working cylinder to a compressing cylinder to fire same in advance of completion of the compression stroke.
13. A combustion engine of the tangentially arranged rotating cylinder type with a driven tubular valve within the shaft, having a transverse cross firing and supercharging passage for connecting a working cylinder to a compressing cylinder to fire same at any point between its outer dead center and the completion of the compression stroke, and means for manually shifting the timing of the cross ignition and supercharging during operation.
14. In a rotary reciprocating combustion engine having a plurality of cylinders each provided with a gas port and combustion space at the inner end, pistons in said cylinders, driving connections for the pistons, means engaging said driving connections for

- rotating the cylinders, the combination with a differentially driven concentric valve for controlling the supply of driving fluid to said cylinders, of means for driving the valve in timed relation to the cylinders, means for discharging a portion of the exhaust through said valve, means for leading off another portion of the exhaust from said cylinders around said valve, and an auxiliary valve controlling the exhaust through said last mentioned means.
15. A rotary reciprocating combustion engine having cylinders with the gas inlet port and combustion space at the inner end, an inlet valve, an exhaust port at the outer end controlled by the piston, and a supplementary valve for preventing back firing through said cylinder exhaust port when the cylinder is charged with fresh gas.
20. 16. A rotary reciprocating combustion engine having cylinders with the gas inlet port and combustion space at the inner end, an inlet valve, an exhaust port at the outer end controlled by the piston, and a valve controlling said exhaust port during a portion of each alternate like piston stroke.
25. 17. A rotary reciprocating combustion engine having cylinders with the gas inlet port and combustion space at the inner end, an inlet valve, an exhaust port at the outer end controlled by the piston, and a supplementary differentially rotatable valve controlling said exhaust port during a portion of each alternate like piston stroke.
30. 18. A combustion engine comprising a cylinder, a piston therein, driving connections for the piston, a tapered valve for controlling the passage of hot gas from the cylinder, a tapered valve seat, means for holding the valve on its seat, means for controlling the unseating effect of cylinder pressure, and means for driving the valve in timed relation to the piston, means for longitudinally shifting the valve on increase of driving torque, and means for passing the main portion of hot gas from the cylinder around said valve.
35. 19. A rotary reciprocating combustion engine having cylinders with the gas inlet port and combustion space at the inner end, a tubular shaft carrying the cylinders, a tubular differentially driven valve body within the shaft having a less number of inlet ports than the number of cylinders and connected at one end to a source of fuel charge and communicating with the cylinder combustion spaces through ports in the shaft and cylinder head, an exhaust port at the outer end of each cylinder controlled by the piston, supplementary exhaust ports in said valve body leading to the opposite end and co-operating with said shaft and cylinder head ports, and a valve controlling said exhaust port during a portion of each alternate like piston stroke.
40. 20. A rotary reciprocating combustion engine having cylinders with the gas inlet port and combustion space at the inner end, a tubular differentially driven valve body within the shaft having a less number of inlet ports than the number of cylinders and connected at one end to a source of fuel charge and communicating with the cylinder combustion spaces through ports in the shaft and cylinder head, an exhaust port at the outer end of each cylinder controlled by the piston, supplementary exhaust ports in said valve body leading to the opposite end and co-operating with said shaft and cylinder head ports, and a valve controlling said exhaust port during a portion of each alternate like piston stroke.
45. 21. A rotary reciprocating combustion engine having cylinders with the gas inlet port and combustion space at the inner end, a tubular differentially driven valve body within the shaft having a less number of inlet ports than the number of cylinders and connected at one end to a source of fuel charge and communicating with the cylinder combustion spaces through ports in the shaft and cylinder head, an exhaust port at the outer end of each cylinder controlled by the piston, supplementary exhaust ports in said valve body leading to the opposite end and co-operating with said shaft and cylinder head ports, and a valve controlling said exhaust port during a portion of each alternate like piston stroke.
50. 22. A rotary reciprocating combustion engine having cylinders with the gas inlet port and combustion space at the inner end, a tubular differentially driven valve body within the shaft having a less number of inlet ports than the number of cylinders and connected at one end to a source of fuel charge and communicating with the cylinder combustion spaces through ports in the shaft and cylinder head, an exhaust port at the outer end of each cylinder controlled by the piston, supplementary exhaust ports in said valve body leading to the opposite end and co-operating with said shaft and cylinder head ports, and a valve controlling said exhaust port during a portion of each alternate like piston stroke.
55. 23. A rotary cylinder combustion engine having a plurality of tangentially arranged cylinders on a hollow shaft, with the gas inlets and combustion spaces at the inner ends, differentially driven inlet valve mechanism for charging each cylinder, and a piston controlled exhaust port in each cylinder leading to the hollow shaft.
60. 24. A rotary cylinder combustion engine having a plurality of tangentially arranged cylinders on a hollow shaft, with the gas inlets and combustion spaces at the inner ends, inlet valve mechanism for charging each cylinder, a piston controlled exhaust port in each cylinder, an exhaust passage leading
65. 125 130

- therefrom to the hollow shaft, and means preventing preignition of a charged cylinder from the shaft exhaust passage.
25. In a rotary cylinder combustion engine having a differentially driven supercharging valve with central gas chamber and transverse passage for supercharging and cross firing a compressing cylinder from a working cylinder, an ignition device in said chamber for starting ignition.
26. In combination with a tubular rotatable valve, a cross ignition chamber body therein, and ported nipples securing the chamber body in the valve body, the nipple ports being in a substantially straight line forming a chord of the valve body.
27. In a combustion engine, a rotor including diverging cylinders, each having a gas port and combustion space at the inner end, a piston in each cylinder, means for reciprocating the pistons during cylinder rotation, a tapered rotary valve concentric with the cylinder movement provided with gas passages, means balancing said valve against unseating by cylinder pressure, and means for driving said valve.
28. In a combustion engine, a rotor including diverging cylinders, each having a gas port and combustion space at the inner end and a piston controlled exhaust port at the outer end, a piston in each cylinder, means for reciprocating the pistons during cylinder rotation, a tapered rotary valve concentric with the cylinder movement provided with gas passages, means balancing said valve against unseating by cylinder pressure, and means for driving said valve.
29. A rotary reciprocating combustion engine having a shaft carrying a multi-cylinder rotor, a conical yieldingly seated valve in said shaft, a cross ignition chamber in said valve, and means connected with said cross ignition chamber for balancing the valve against unseating by cylinder pressure.
30. In a combustion engine, a rotor including diverging cylinders, each having a gas port and combustion space at the inner end, a piston in each cylinder, means for reciprocating the pistons during cylinder rotation, a tapered rotary valve concentric with the cylinder movement provided with supply and exhaust passages, transverse passages between said supply and exhaust passages for firing a succeeding from a working cylinder, means balancing said valve against unseating by cylinder pressure, and means for driving said valve.
31. A combustion engine comprising a cylinder, a piston therein, driving connections for the piston, a tapered valve for controlling the passage of hot gas from the cylinder, a tapered valve seat, means for holding the valve on its seat, means for controlling the unseating effect of cylinder pressure, and means for driving the valve in timed relation to the piston, and means for adjusting the timing of said valve during rotation.
32. In a rotary reciprocating combustion engine, the combination with a plurality of cylinders, of a shaft on which the cylinders are mounted, pistons within the cylinders, means connected to the pistons for producing rotation of the cylinders, a valve within said shaft, supply, exhaust, and cross-firing ports in said valve, and another exhaust port in the side wall of said cylinders.
33. The combination with a plurality of cylinders, of a shaft on which the cylinders are mounted, pistons within the cylinders, means connected to said pistons for producing rotation of the cylinders, a valve within the shaft, means for driving said valve at a different speed with respect to the cylinders, supply, exhaust, and cross-firing ports in the valve, other exhaust ports in the side walls of the cylinders, and an auxiliary valve controlling the second mentioned exhaust ports.
34. In a rotary reciprocating combustion engine, the combination with a plurality of cylinders, of a shaft on which the cylinders are mounted, pistons within the cylinders, means connected to the pistons for producing rotation of the cylinders, a valve within said shaft, supply ports in the valve, an exhaust passageway in the side wall of each cylinder controlled by the piston, an auxiliary valve for controlling said exhaust passageway, and means for adjusting the timing of said auxiliary valve while the engine is rotating.
35. In a rotary reciprocating combustion engine, the combination with a plurality of cylinders, of a shaft on which the cylinders are mounted, pistons within the cylinders, means connected to the pistons for producing rotation of the cylinders, a valve within said shaft, supply, exhaust, and cross-firing ports in the valve, means for differentially driving said valve with respect to the cylinders, and a mechanical mixing device located within the valve for thoroughly mixing the vapor and air supplied to said cylinders.
36. A rotary reciprocating combustion engine having diverging cylinders with the gas inlet port and combustion space at the inner end, an inlet valve, an exhaust port at the outer end, and a supplementary valve carried by the inlet valve controlling said exhaust port.
37. In a combustion engine, a rotor including diverging cylinders each having a gas port and combustion space at the inner end, a piston in each cylinder, means for reciprocating the pistons during cylinder rotation, a valve concentric with the cylinder movement for controlling a portion of the exhaust from said cylinders, means for driving the valve in timed relation to the cylinders, means for passing the main exhaust around said valve, and internally connected passages in said valve jacketed from the valve body for trans-

ferring incandescent gas from a working to a succeeding cylinder.

38. In a combustion engine, a rotor including diverging cylinders each having a gas port and combustion space at the inner end, a piston in each cylinder, means for reciprocating the pistons during cylinder rotation, a rotary tapered valve concentric with cylinder movement for transferring incandescent gas from a working to a succeeding cylinder, a tapered valve seat, means for holding the valve on its seat, means balancing the valve against cylinder pressure, means for driving the valve in timed relation to the cylinders, and means for varying the timing of the valve during rotation.

39. In a combustion engine, a rotor including diverging cylinders each having a gas port and combustion space at the inner end, a piston in each cylinder, means for reciprocating the pistons during cylinder rotation, a rotary valve concentric with the cylinder movement and having an internal transverse passage for transferring incandescent gas from a working to a succeeding cylinder, means for driving the valve in timed relation to the cylinders, and main exhaust means independent of the valve.

40. In a combustion engine, a rotor including diverging cylinders each having a gas port and combustion space at the inner end, a piston in each cylinder, means for reciprocating the pistons during cylinder rotation, a rotary tapered valve concentric with the cylinder movement for controlling a portion of the exhaust from said cylinders, means for driving the valve in timed relation to the cylinders, a tapered valve seat, means for holding the valve on its seat, means responsive to increase in its driving torque for longitudinally shifting the valve, and main exhaust means independent of said valve.

41. In a combustion engine, a rotor including diverging cylinders each having a gas port and combustion space at the inner end, a piston in each cylinder, means for reciprocating the pistons during cylinder rotation, a valve concentric with the cylinder movement for controlling the supply of fuel to said cylinders and having a transverse passage for igniting a succeeding from a working cylinder, and means for exhausting said cylinders independently of said valve.

42. In a combustion engine, a rotor including diverging cylinders each having a gas port and combustion space at the inner end, a piston in each cylinder, means for reciprocating the pistons during cylinder rotation, a rotary tapered valve concentric with the cylinder movement for passing incandescent gas from a working to a succeeding cylinder, a tapered valve seat, means for holding the valve on its seat, means for controlling the unseating effect of cylinder pressure, and means for driving the valve in timed relation

to the cylinders, and means responsive to increase in its driving torque for longitudinally shifting the valve.

43. In a combustion engine, a rotor including diverging cylinders each having a gas port and combustion space at the inner end, a piston in each cylinder, means for reciprocating the pistons during cylinder rotation, a rotary tapered valve concentric with cylinder movement for passing incandescent gas from a working to a succeeding cylinder, a tapered valve seat, means for holding the valve on its seat, means for controlling the unseating effect of cylinder pressure, and means for driving the valve in timed relation to the cylinders, means responsive to increase in its driving torque for longitudinally shifting the valve, and means for adjusting the timing of the valve during rotation.

44. In a combustion engine, a rotor including diverging cylinders each having a gas port and combustion space at the inner end, a piston in each cylinder, means for reciprocating the pistons during cylinder rotation, a tapered valve concentric with the cylinder movement for controlling a portion of the exhaust from said cylinders, means for passing another portion of the exhaust around said valve, a tapered valve seat, means for holding the valve on its seat, and means for longitudinally shifting the valve in response to increase in its driving torque.

45. In a combustion engine, a rotor including cylinders, each having a gas port and combustion space at their adjacent ends, a piston in each cylinder, means for reciprocating the pistons during cylinder rotation, a valve concentric with cylinder movement and having an internal passage spaced from the valve body for transferring incandescent gas from a working to a succeeding cylinder.

46. In a combustion engine, a rotor including cylinders, each having a gas port and combustion space at their adjacent ends, a piston in each cylinder, means for reciprocating the pistons during cylinder rotation, a valve concentric with the cylinder movement having a combustion chamber therein, an internal passage connected with said chamber for transferring incandescent gas from a working to a succeeding cylinder, and means spacing said chamber from the valve body.

47. A combustion engine comprising a rotor having diverging cylinders, pistons therein, actuating means for the pistons, a tapered concentric valve, a tapered valve seat, means holding the valve on the seat, means for balancing unseating cylinder pressure, means for driving said valve in timed relation to the cylinders, and means for adjusting the valve timing during rotation.

48. A fluid expansion engine having a cylinder, a piston therein, driving means for the piston, a tapered valve controlling the

passage of cylinder fuel, a tapered valve seat, means for holding the valve on its seat, means for balancing unseating cylinder pressure, means for driving said valve in timed relation to the piston, and means for longitudinally shifting the valve against said holding means in response to increase in its driving torque.

5

ports than the number of cylinders for supplying fuel charge through said port, an exhaust port at the outer end of each cylinder, supplementary exhaust ports in said valve body connected to the inner end of each cylinder, the passages from each exhaust port being connected, and means carried by the valve body preventing back fire.

49. In a combustion engine, a rotor having diverging cylinders with a gas port and combustion space at the inner end, a tubular driven valve body concentric with the cylinder movement having a less number of inlet
